UNITED STATES PATENT OFFICE

2,429,870

APPARATUS FOR COATING WIRE
AND THE LIKEWalter G. Dahlstrom, Worcester, Mass., assignor
to The American Steel and Wire Company of
New Jersey, a corporation of New Jersey

Application June 8, 1944, Serial No. 539,344

4 Claims. (Cl. 91—32)

1

The present invention relates to improvements in apparatus for the application of a liquid coating material to a moving body such as a cord, wire, or cable.

Heretofore, in the application of coating materials to flexible bodies such as a traveling wire or the like, it has been the custom to use a die fixedly mounted and equipped with external adjusting mechanism for guiding the moving body through the axial bore of the die. This prior practice is open to the objection that any slight changes in the external setting of the die mounting, or variations in conditions inherent in the construction and operation of the devices, has caused the body such as the wire or cable being coated to be deflected from the true axis of the die opening, and this has resulted objectionably in the application of uneven coating on the moving body.

The chief object of the present invention is to overcome deficiencies inherent in prior coating practice, and to provide apparatus which will insure an even or uniform distribution of coating material over the advancing cord, wire, or cable.

A further object of the invention is to provide means for floatingly supporting a coating-distributing die by a buoyant fluid so that the coating material applied to the wire or similar moving body is uniformly distributed over the exterior surface thereof.

The above and related features of the invention will be more fully apparent from a consideration of the following detailed disclosure, the accompanying drawings, and the appended claims.

In the drawings:

Figure 1 diagrammatically illustrates an installation for giving effect to the herein claimed invention.

Figure 2 is an enlarged vertical section illustrating means for floatingly supporting the coating distributing die by a buoyant fluid.

Figure 3 is a plan view of Figure 2.

Referring in detail to the drawings, the numeral 10 represents a reel carrying a supply of wire or cable 12 which is adapted to be coated. The wire passes downwardly around a guide sheave 14 mounted in a tank 16 containing a body of liquid coating material 18 such as various liquid or semi-plastic insulating compounds. The body to be coated passes upwardly through a tubular member 20 and thence through a die 22 secured to a float 24 which is buoyantly supported by a body of liquid 26 held in a container 28 which may be conveniently supported on the tube 20. The tube 20 in turn may be supported

2

by a hub 30 forming part of a spider-like skeleton frame 32 having an annular rim 34 fitted to the tank 16.

The die 22 has an externally threaded shank 36 so as to removably secure it to the float. Thus the same float is adapted to support dies having different sizes of axial bores 38 for operation on different gauges of wire. The axial bore is flared or tapered at its entrance end, as indicated at 40. At its upper portion the die carries a flange 44 adapted to have one or more slotted weights 46 seated thereon.

The wire or cable to be coated may be pulled through the apparatus by any suitable means known to those skilled in the art. By way of example I have illustrated a pull-out including a pair of drums or capstans 48 and 50 around which the wire will be wound several times. From the capstan 50 the coated wire or cable passes to the take-up drum 52. A motor 54 and suitable transmission elements are provided for driving the capstan 50 and take-up reel 52.

In coating wire by the improved apparatus of the present invention, the body to be coated passes through the coating liquid 18, and a quantity of the material, depending upon the viscosity thereof and the speed of travel of the body, will adhere thereto and be carried upwardly to the tapered or conical entrance 40 of the die.

The coating substance, because of its viscosity and the speed of application, will exert a force on this tapering or conical entrance portion of the die bore which may be resolved into horizontal and vertical components. The vertical component of the force will be opposed by gravity and the weight of the die and adjustable weights 46 supported thereon. The horizontal component of the force exerted on the tapered or conical die entrance, because of the buoyancy of the die support, will be distributed equally throughout the surface area and thus cause the moving body such as the wire or cable 12 to travel at all times through the die bore 38 in a line truly coincident with the axis of the die, hence resulting in an even or uniform distribution of the coating material on the moving body. The liquid 26 which buoyantly supports the float 24 which in turn supports the die in a self-centering manner, may be water, glycerine, mercury, or other fluids, depending upon the buoyancy required to support the float, the die, and the weights 46, when the latter are used. By calculation, the weight of the float and the die can be determined so that a correct balance will be kept between them and the force exerted by the coating material at the

conical entrance 40 of the die. However, for practical purposes it is advantageous to provide adjustable weights 46 to compensate for the added speed of coating or greater viscosity of coating material in order that a correct balance will be maintained between the weight of the die and its float and the forces exerted at the conical entrance, thus providing means whereby a die having a predetermined bore diameter may be used for different viscosities of coating material and speeds of wire travel through the die.

While I have herein illustrated and described a preferred means for making the invention available, it is not to be construed that I am limited thereto, since various modifications and substitutions of equivalents may be resorted to by those skilled in the art without departure from the invention as defined in the appended claims.

I claim:

1. Apparatus for coating wire, comprising means for applying coating material thereto, a die having an upright opening therein through which the coated wire passes, a container for a buoyant medium, a die-supporting member floating in said medium, the die having a tapering entrance bore, and weights seated on the float adapted to compensate for variations in the viscosity of the coating material and the rate of travel of the wire through the die, so that a correct balance is maintained between the weight of the die and float and forces exerted at the conical entrance of the die, thus adapting a die of given size for use for different viscosities of coating material and different rates of travel of the wire through the die.

2. Apparatus for coating wire, comprising means for holding a supply of coating material, means for guiding the wire through said coating material, a tubular member through which the wire passes upon emergence from the coating

material, a container spaced above the level of the coating material and secured to the tubular member and carrying a body of liquid, a float buoyantly supported by said liquid, and a die carried by the float having a passageway therein through which the wire passes after being coated.

3. Apparatus for coating wire, comprising means for applying coating material thereto, a die having an upright opening therein through which the coated wire passes, a container for a buoyant medium, and a die supporting member floating in said medium, the die having a bore with an entrance portion converging toward the exit end thereof.

15 4. Apparatus for coating a flexible tenuous article, comprising means for applying coating material thereto, a die having an upright vertical opening through which the article passes, a container for a buoyant medium, and a die supporting member floating in said medium, the die having an elongated substantially parallel walled bore with a flared entrance portion converging toward said bore.
